Application February 26, 1932, Serial No. 595,324
 Renewed September 12, 1935

31 Claims. (Cl. 20—16)

The present invention relates to doors and improved means of mounting them for sliding and swinging movement to and from an open and closed position; said means being easy to operate 5 and simple to construct and assemble.

More specifically, the invention comprises a door and door mounting construction wherein the door is balanced, so to speak, to render the same easy to open and to maintain closed against 10 high wind pressures and other disturbing influences. Where doors are used for service in entrances and vestibules of office and public buildings, they are required to swing outwardly and the wind pressure thereagainst often makes them 15 extremely difficult to operate. In doors of this character, door closers must be used which exert pressure upon the doors to maintain them closed against wind pressure from the inside, as for example, due to a current of air from the vestibule. The pressure required in these door closers 20 adds to the difficulty of opening the doors and thus frequently becomes objectionable.

The present invention proposes to balance doors of this character by mounting them in 25 such fashion that part of the door swings inwardly while the other part swings outwardly. In this fashion, the pressure exerted upon one side of the door is in substantial equilibrium in view of the fact that part of such pressure tends 30 to open the door and part tends to maintain the same closed. This construction obviously requires less normal pressure to maintain the door closed and hence permits a door closer construction to be employed having a comparatively slight 35 spring pressure.

Furthermore, the construction is such that all 40 of the parts may be conveniently contained within the door to avoid unsightly projections and irregular contours and to permit free application 45 of architectural design. The door construction is further adapted to receive all modern improvements which it is desired to apply thereto and is of adequate strength to withstand the severe stresses and strains impressed thereon when in use.

An object of the invention, accordingly, is to provide an improved door mounting means whereby wind pressures upon the sides of a door may be equalized and the resistance heretofore produced thereby eliminated. 50

A further object of the invention is to provide a door mounting mechanism of the above character wherein a door closer may be utilized having a comparatively slight spring pressure serving 55 to maintain a door normally closed.

A further object of the invention is to provide a construction of the above character, wherein the mounting and auxiliary elements are maintained within the door in order that the architectural design and beauty of the door may be 5 preserved.

A further object of the invention is to provide an improved door mounting mechanism by means of which the adjustable spacing of the door vertically may be effected.

A further object of the invention is to provide an improved door closing mechanism.

A further object of the invention is to provide a closing mechanism for doors, wherein the mechanism is contained within the door structure and mullion.

A further object of the invention is to provide an improved door mounting and closing mechanism, wherein the wind pressure upon the door may be equalized in such fashion that no resistance to opening or closing thereof results, and at the same time providing a door closing mechanism which offers a comparatively slight resistance to such movement.

A further object of the invention is to provide an improved holding mechanism for holding a balanced door in its open position.

A further object of the invention is to provide a mounting mechanism for balancing doors against wind pressures, such mechanism including mounting arms in combination with a straightening out or door closing mechanism, as well as a door check.

A further object of the invention is to provide a mounting mechanism for doors of the above 35 character by means of which the same may be readily installed and dismounted, the mechanism further being adapted for use in connection with jambs of varying height.

Further objects not specifically enumerated 40 above, will become apparent or be referred to as the invention is described in greater detail in connection with the accompanying drawings, wherein:

Figure 1 is a view in front elevation, showing 45 a door and door mounting mechanism constructed in accordance with the present invention.

Figure 2 is a view in section, taken on line 2—2 of Figure 1, and looking in the direction of the arrows, showing the door mounting mechanism 50 in plan.

Figure 3 is a view similar to Figure 2 showing one door moved to a fully open position and another door moved to a partially opened position.

Figure 4 is a view in section, taken on line 55

4—4 of Figure 2, and looking in the direction of the arrows, this figure showing the straightening out device for a door constructed in accordance with the present invention, also the 5 door check device, adjustable hinge pin, and a device for holding the door in an open position.

Figure 5 is a view in section, taken on line 5—5 of Figure 4, looking in the direction of the arrows and showing a plan view of the device 10 for holding the door in open position.

Figure 6 is a view in section, taken on line 6—6 of Figure 4, and looking in the direction of the arrows, this view shows the upper door mounting arm secured to the top of the hinge and 15 connected to the top of the door and also illustrates how the arms may be made in two pieces if desired, to reduce the cost of manufacturing and maintaining a stock of such arms of different sizes to be used in hinging doors of various 20 widths at either the right or left hand edges thereof.

Figure 7 is a view in section, showing the lower bearing for the door mounting mechanism with the lower door mounting arm secured to the bottom 25 of the hinge and connected to the bottom of the door, together with the manner of adjusting the tension on the coiled spring mounted in said hinge.

Figure 8 is a view in section, taken on line 30 8—8 of Figure 7, and looking in the direction of the arrows, and showing, in dot and dash lines, the door in open position.

Figure 9 is a view in section, taken on line 35 9—9 of Figure 7, and looking in the direction of the arrows.

Figure 10 is a view in section, taken on line 10—10 of Figure 4, and looking in the direction of the arrows.

Figure 11 is a view in section, taken on line 40 11—11 of Figure 4, and looking in the direction of the arrows.

Figure 12 is a view in section, taken on line 12—12 of Figure 4, and looking in the direction of the arrows.

Figure 13 is a view in section, taken on line 45 13—13 of Figure 4, and looking in the direction of the arrows.

Figure 14 is a view in section, taken on line 50 14—14 of Figure 4, and looking in the direction of the arrows.

Figure 15 is a view in section, taken on line 15—15 of Figure 6, and looking in the direction of the arrows.

Figure 16 is a view in section taken on line 55 16—16 of Figure 1 and looking in the direction of the arrows.

Figure 17 is a view in section, taken on line 17—17 of Figures 3 and 16, and looking in the direction of the arrows.

Figure 18 is a view showing the mechanism for 60 adjusting the tension on the hinge spring of the door.

Figure 19 is a view in section, taken on line 65 19—19 of Figure 18 and looking in the direction of the arrows.

Referring to the above drawings, a door of any 70 desired shape or design is shown at 20. A handle 21 and push bars 22 are mounted thereon in the usual fashion. The door is adapted to be swingably and slidably mounted in a suitable doorway formed by a floor 23, a cornice 24 and hollow mullions 25, on a tubular hinge or pivot means 26 disposed within the mullions and upper and lower arms 27 and 28 welded, brazed or otherwise secured at the ends of the hinge.

Referring now to Figure 7, it will be seen that a collar 30 is formed on the upper side of the lower arm 28 and is adapted to fit into the lower end of the tubular hinge 26 to which it is securely fastened or welded thereto as above described. The lower side of the arm 28 is formed to receive a ball step or thrust bearing 31 adapted to support the weight of the door 20 in a manner to be hereinafter described. Mounted in the floor 23 is a gear box 32 to which the mullions 25 and thresholds 33 are secured, see also Figures 18 and 19. A gear 34 having a hub 35 on the bottom face thereof is rotatably mounted in a bearing 36 formed in the bottom of the gear box 32; the gear 34 being held in position by a plate 37 which 15 is fastened to the gear box by screws 38. The plate 37 surrounds a hub 39 formed on the upper face of the gear 34 and is adapted to hold the gear 34 in the bearing 36. A key 40 is secured 20 in notches 41 formed in the sides of a counterbore 42 cut in the upper face of the gear in any suitable manner. As here shown the key 40 is secured in the notches 41 by swaging the sides of the notches against the key, as shown at 43 in Figure 18. A stud 44, having a kerf 45 cut 25 in the head thereof and adapted to engage the key 40, is screwed into the end of a shaft 46 against the lower race 47 of the thrust bearing 31 and locked therein by means of a pin 48. The shaft 46 is revolubly mounted in the hinge 26 30 in a bearing 49 formed through the hub of arm 28 and the collar 30 above described.

A spring 52, having one end disposed over a pilot 53 and located in a notch 54 formed in the shaft 46 and the other end disposed over a plug 35 55 and located in a notch 56, both of which are anchored to the hinge 26 by a pin 51, serves to hold the door 20 closed or to close said door when it is open, as will more fully appear hereinafter. The shaft 46 is held in position, with the race 47 40 against the balls of the thrust bearing 31, by means of a circular plate 61 and gasket 62 secured to the bottom of the arm 28 and disposed around the head of the stud 44. Oil holes 63 are provided in the hinge 26 and collar 30 for oiling the 45 bearing 49, and the gasket 62 above described is adapted to prevent oil from leaking from said bearing. The elevation of the hinge 26 and arm 28 may be varied with respect to the thresholds 33 and gear 34 by means of shims 64 disposed in the 50 bottom of the counterbore 42 under the head of the stud 44.

Referring now to Figures 18 and 19 it will be seen that a pinion 67 meshing with the gear 34 is mounted in a bearing 68 formed in the bottom 55 of the gear box 32. The pinion is provided at its center with a square hole 69 so that by means of a similarly shaped wrench or key, not shown, it may be rotated at will to turn the gear 34 and adjust the tension of the spring 52 as hereinafter 60 described. A dog 70, urged to coact with the teeth of the gear 34 by a spring 71, is mounted in the bottom of the gear box 32, to hold the gear 34 in any desired position. A removable plate 72, see Figure 8, is fastened to the gear box 32 over the 65 pinion 67 and dogs 70, by means of screws 73, so as to give ready access to these parts for the adjustment of the tension of the spring 52.

From the mechanism thus far described, it will be seen that the hinge 26 and arm 28 are supported by the gear 34 and adapted to rotate on the thrust bearing 31 and moreover that when the pinion 67 is rotated in a clockwise direction, the gear 34, key 40 and stud 44 will be rotated in a counter-clockwise direction and put a tension 75

on the spring 52 which will serve to urge the arms 27 and 28, or particularly the hinge 26, to rotate in a counter-clockwise direction and assist in closing the door 20 or to serve as a means of holding said door closed.

The upper end of the hinge 26 carries an axially movable pin 76 which is received within a bearing 77, formed in the upper arm 27 and a collar or bushing 78 formed thereon. The bushing 78 of the arm 27 is welded to the hinge 26 as above described. A slot 79 formed in the hinge 26 receives set screws 80 which are screwed into the pin 76. By removing the lower set screw, see Figure 13, the pin may be dropped to the position indicated in dot and dash lines and the door easily removed. In the position shown in solid line the pin 76 engages a bearing 81 located in one end of a channel bracket 82 mounted within the cornice 24 and thus the door 20 is hung in a suitable manner on hinge or pivot means 26 and arms 27 and 28, as above described. It will be seen from Figure 1 that the upper and lower arms 27 and 28 extend horizontally from the upper and lower ends of the hinge 26 respectively.

The extremity of the lower arm 28 is constructed to form a pivotal connection with the door and includes a socket 85 adapted to receive a hardened disc 86 and a cup 87. The cup 87 is provided with a convex bottom 88 and a rounded annular rib 89 whereby it is adapted to variously position itself in the socket 85 on the disc 86. A downwardly extending bearing 90, carried by a bracket 91 which is secured to the bottom of the door 20 in a recess 92, is adapted to fit into the cup 87. A hardened disc 93, having a key 94 adapted to fit in a notch in the bottom of the bearing 90 and a second hardened disc 95, are disposed in the bottom of the cup 87. An oil hole 96 is provided in the bracket 91 through which the bearing 90, discs 93 and 95 may be oiled. From Figures 1, 7 and 9, it will be seen that the parts just described are adapted to furnish support for the bottom of the door 20 and that when said door is closed the arm 28 will fit into recess 92 so as not to constitute an objectionable interruption to the even surface and contour thereof.

The upper arm 27, see Figures 4 and 6, engages a shaft 99, having a squared end, for supporting the top of the door and operating a door closure and check in a manner which will be described hereinafter; the axis of the squared shaft 99 being aligned with the axis of the bearing 90 and cup 87 in order that the door may be journalled or have a pivotal connection with each arm upon a single vertical axis which lies between the edges thereof.

It will be seen from Figure 15 that the faces of the shaft 99 are provided with rounded ribs 100 and adapted to fit into a hardened bearing 101 secured in the end of the arm 27 by means of rivets 102. The rib 89 on the cup 87 and the rib 100 on the shaft 99, with which the lower and upper arms cooperate respectively serve to permit these parts to properly adjust themselves, notwithstanding they may be slightly out of alignment. The swinging movement of the door 20 is therefore fixed by the hinge 26 and the vertical axis passing through the extremities of the arms 27 and 28.

The sliding movement of the door is guided by means of a ball bearing roller 103 journalled upon a stub shaft 104 mounted upon the top of the door. The roller 103 is adapted to travel in the channel bracket 82, which is mounted within a soffit of the cornice 24 by means of screws 105, and

depending lugs 106 adapted to fit into the top of the mullion 25, see Figures 4, 13 and 17. The roller 103 thus imparts a sliding movement to the door while the arms 27 and 28 impart a swinging movement thereto as above described. The arms 27-28, in combination with the portion of the door between the axis of the shaft 99 and roller 103, constitute a toggle which is utilized in a manner hereinafter described to facilitate the closing and opening of the door.

Within the upper wall of the channel bracket 82 a detent or door holder 107 is mounted to rock on a bolt 108, see Figures 4 and 5. A finger hole 109 is formed in the detent to facilitate its adjustment to and from the position shown in Figures 4 and 17 respectively. A ball 110, urged by a spring 111 confined in a housing 112 formed on the top of the bracket 82 by means of a pin 113, is adapted to fit into depressions 114 in the face of the door holder 107 to retain said holder 107 in an inoperative position as shown in Figure 4 or in an operative position as shown in Figure 17. A stop 115, formed on the end of the holder near the bolt 108 and stops 116 formed at the upper edge of the face of the holder, serve to limit the movement thereof to the positions above described.

Within the door, and preferably at the top thereof adjacent the shaft 99 is a cylinder 120 provided with heads 121 and 122. A coil spring 123 having a diameter adapted to permit it to be compressed against the head 122 by the axial movement of a reciprocating piston 124 is mounted within the cylinder 120. The piston 124 is formed with rack teeth 125 which engage a pinion 126 mounted upon or formed integrally with the squared shaft 99 and thus relative rotation between the door 20 and arm 27 cause the shaft 99 and pinion 126 to move the piston 124 reciprocally within the cylinder 120. A piston 40 head 127, snugly engaging the cylinder walls, is formed at one end of the piston 124, which, with the end of the cylinder that is closed by the head 121, forms a chamber within which fluid may be compressed to check the closing of the door. A duct or passage 130, see Figure 10, is formed in the piston 124 by milling a kerf 131 in the lower side of the piston 124 behind the rack teeth 125 and drilling a hole 132 through the piston head 127 into said kerf, see Figure 4, for the passage 50 of fluid from the end of the cylinder in which the spring 123 is located, to the compression end 133, of the cylinder. The end of the hole 132 in the piston head 127 is enlarged and formed to provide a seat 134 for a ball 135 to prevent the 55 flow of fluid through the passage 130 when the piston is forced toward the head 121 and to permit said flow when the piston is moved toward the spring 123 and head 122. The ball 135 is retained in the opening at the middle of the hole 132 and in proximity to the seat 134 by pins 136 and 137. Obviously, other means may be employed by which the passage 130 may be made to perform the functions above mentioned and I am not to be understood to limit this part of my invention to 65 the specific means here illustrated and described.

From Figures 4, 10, 11 and 12 it will be seen that the cylinder 120 forms a part of a casing 140 having an offset portion 141 in which the pinion 126 is housed and mounted by means to be herein- 70 after described. The casing 140 also comprises a fluid chamber 142 in communication with the cylinder 120 and a plate or tongue 143 extending from one side thereof to which the stub shaft 104 and roller 103 are mounted. The casing 140 is 75

fastened to the top of the door, in an opening provided therefor, by screws 144 passing through the plate and a screw 145 passing through the back edge of the door into the body of the casing, 5 see Figures 6 and 16.

From Figure 11 it will be seen that a bushing 146 is threaded into the top of the offset 141 to hold the pinion 126 in a bearing 147 formed in the bottom of the offset 141 and that a bushing 10 148 and packing 149 in the bushing 146 serve as a bearing for the shaft 99. A set screw 150 is provided to lock the bushing 146 in its proper position. Adjacent the squared shaft 99 the top 15 of the casing is cut away at 151, see Figures 6, 11 and 16, to permit the nesting of arm 27 therein when the door 20 is in closed position.

The casing 140 and cylinder 120 is filled with a fluid medium to afford the desired gradual checking effect to the door, and the piston within the 20 cylinder. A duct 154 is formed in the casing 140 and is adapted to communicate with the cylinder 120 through the chambers 142, ports 155 and 156 leading from said duct 154 to the cylinder. The duct 154 communicates with the region of the 25 cylinder back of the piston head through the chambers 142 while the ports 155 and 156 communicate with the compression end, 133, of the cylinder. The outward end of the duct 154 is closed by a set screw 157. The size of the port 30 155 is adapted to be variably controlled by a needle valve 158 mounted in the casing 140 in any suitable well known manner. The passage of fluid through the port 156 is controlled by ball 35 check valve 159 which, by means of a seal 160 is sealed in position after the mechanism is assembled and ready for use. An opening adapted to be closed by a screw 161 is provided for the introduction of the fluid medium, such as oil, glycerine or the like for filling the cylinder 120 and associated voids.

From the above it will be seen that when the doors shown in Figure 2 are opened to the positions shown in Figure 3 the upper arm 27 will rotate the pinion 126 in a clockwise direction 45 with reference to the door 20. By virtue of such rotation of the pinion 126 the piston 124 will move from the compression end, 133, of the cylinder 120 toward the spring 123 and when the piston 124 comes in contact with the spring 123 50 it will continue so to move until the door is fully opened. One purpose therefore of the spring 123 is to cushion the door when it is suddenly opened to full open position and another purpose is to serve as a means of affording an initial assistance 55 toward closing the door when desired. The pinion 126 and piston 124, irrespective of their door checking function, also provide means for delaying the tensioning of the second spring 123 until the door is partially open. The pinion and 60 piston have, therefore, a double function of providing a door check and a delaying means for tensioning the second spring 123, which functions are joined in the one structure for the purpose of simplifying the construction.

65 As the piston 124 is moved toward the spring 123, fluid from the spring end of the cylinder 120 will flow through the piston past the valve 135 into the compression end of the cylinder. When the door starts to close the valve 135 will close 70 against the seat 134 and prevent the passage of fluid through the passage 130 such that the only escape for the fluid which is trapped in the compression end, 133, of the cylinder 120 is through the ports 155 and 156, the duct 154 and 75 the fluid chamber 142 to the spring end of the

cylinder. At first, such fluid will escape through both ports 155 and 156. This will continue until the piston head 127 passes and closes the port 156 and thereafter during the final closing movement of the door, all fluid trapped in the compression end of the cylinder must pass through the port 155. Having provided the needle valve 158 for controlling the size of the port 155, as above described, I am able to control the rate at which the door is finally closed.

10 The construction described is very effective as will now be discussed. The broader aspect of the invention deals with the toggle formed by the arm 27 and the door with the respective three pivot points 76, and 99 shown in Figure 10, and 15 the guide means roller 103. The toggle is best shown in Figure 3. Now a spring 52 tends to rotate the arm 27 when the door is open to close the door. Any such spring means, of course, has its maximum tension when the door is open and 20 minimum tension when the door is closed. Because of this fact, a substantial initial tension is usually applied to the spring in order to insure that the door will close. In the construction herein, a decreasing tension in the spring 52 as 25 the door closes is compensated for by an increasing power advantage in the toggle, that is, as the toggle approaches straightened position its mechanical advantage is greatest, thereby transforming the lesser spring force into an increasing 30 door closing effort because of the toggle.

Again, when the door is in full open position, the toggle, represented by the arm 27 and the door with the pivots 76, 99 and 103, is in a position where the force of the spring 52 is least effective to close the door. In order to augment the spring in this position, a second spring means 123, Figure 4, is provided which acts upon the pivot 99 to rotate it and the door and aids particularly the initial door closing movement.

40 Attention is also called to the door check which has been applied to the pivot 99 or the pivot at the knee of the toggle in combination with a door closing spring 52 applied to one of the arms of the toggle, or particularly to the pivot for the 45 arm 28. The door check applied at the pivot at the knee of the toggle or pivot 99 provides a pivot having twice the extent of rotation, as compared with the rotation of the pivot for the arm 28 which is the usual point of application of a 50 door check, or at the pivot 103. This greater extent of rotation of the pivot 99 effects a more accurate and more easily controlled door check.

From the foregoing it will be seen that my door mounting mechanism comprises a spring 52, the 55 tension of which is increased during the time the door is being opened and during the time tension is being stored in the spring 123 in the cylinder 120, so that the initial tendency toward closing the door is simultaneously supplied by the spring 60 52 in the hinge and the spring 123 in the cylinder. Having provided means for varying the tension on the spring 52, I am able to regulate the pressure necessary to open the door and also the spring tension, or force, which tends to close 65 the same.

From the foregoing, it will also be seen that a door mounting structure has been provided which is simple of construction and of great strength. The elements are few in number and 70 are readily assembled and afford an effective means for hanging a door at a desired height. Provision is made for swinging the door in doorways of slightly varying dimensions without requiring a material change in the structure, thus 75

adding to the convenience of the device and the ability to standardize the parts thereof. Movement of the door to and from open and closed positions is effected with facility in view of the fact that a portion of the door swings in while another portion swings out, thus balancing the effective pressures upon the sides thereof to prevent wind pressure, etc., from resisting such movement. The toggle effect of the mounting mechanism including the arm 27 and pivot connections of the door thereto, in addition to a portion of the door between such pivot connections and the guide rollers 103, facilitate a checking of the movement of the door as it approaches a closed position. The means for straightening out the toggle elements and thus closing the door is simple in construction and contained within the door and mounting itself, thus improving the appearance thereof and permitting doors of any design to be used. Combined with the straightening out elements is a door check described above, and a door closing spring mounted in the hinge and these devices, being formed as a unit, add to the simplicity of the structure.

25 While the invention has been described with specific reference to the accompanying drawings, it is not for this reason to be understood as limited save as defined in the appended claims.

What I claim is:

30 1. Means for mounting a door comprising a hinge mounted in a doorway for supporting a door between the vertical edges thereof, a spring disposed in the hinge for closing said door, and means for variably tensioning said spring, said tensioning means comprising an anchor and a shaft in said hinge to which the ends of said spring are respectively fixed, means mounted in the floor for rotating said shaft and means for locking said shaft in various positions.

40 2. Means for mounting a door comprising a hinge mounted in a doorway for supporting a door between the vertical edges thereof, a spring disposed in the hinge for closing said door, and means for variably tensioning said spring, said tensioning means comprising an anchor and a shaft in said hinge to which the ends of said spring are respectively fixed, a gear mounted in the floor and fixed to said shaft for rotating said shaft and a dog for locking said shaft in various positions.

50 3. Means for mounting a door comprising a hinge mounted in a doorway for supporting a door between the vertical edges thereof, said hinge comprising a tube and a pair of laterally extending arms rigidly secured to the ends thereof; a spring disposed in the tube for closing said door, and means for variably tensioning said spring, said tensioning means comprising an anchor and a shaft in said tube to which the ends of said spring are respectively fixed, means mounted in the floor for rotating said shaft and means for locking said shaft in various positions.

45 4. A door organization comprising in combination, a door, a door check, a hinge mounted in a doorway for supporting the door between the vertical edges thereof, means for operatively connecting said hinge to the door check, a tensioned spring for closing the door, said door check comprising means adapted to be progressively tensioned during the door opening movement to yieldingly limit the extent to which the door may be opened and to assist the door closing spring in closing said door.

55 5. A door organization comprising in combination, a door, a door check, a tubular hinge

mounted in a doorway for supporting the door between the vertical edges thereof, said hinge comprising a pair of laterally extending arms rigidly secured to the ends thereof, one of said arms being operatively connected to the door check, a tensioned spring disposed in the tubular hinge for closing the door, said door check comprising a cylinder, a piston, means operated by the relative movement between the door and hinge to move said piston to and fro in said cylinder, and a spring in said cylinder adapted to be compressively tensioned by the piston during the latter part of the door opening movement to yieldingly limit the extent to which the door may be opened and to assist the hinge spring in closing said door.

60 6. A door organization comprising in combination, a door, a door check, a hinge mounted in a doorway for supporting the door between the vertical edges thereof, said hinge comprising a pair of laterally extending arms rigidly secured to the ends thereof, one of said arms being operatively connected to the door check, a tensioned spring operatively connected to the hinge for closing the door, means for increasing the tension on said hinge spring as the door is opened, said door check comprising a cylinder, a piston, means operated by the relative movement between the door and hinge to move said piston to and fro in said cylinder, and a spring in said cylinder adapted to be compressively tensioned by the piston during the latter part of the door opening movement to yieldingly limit the extent to which the door may be opened and to assist the hinge spring during the initial part of the door closing movement in closing said door.

65 7. A door organization, comprising in combination, a door; hinge means for the door including, an arm, pivot means for the arm supporting the door proximate a doorway, and a pivotal connection between the outer end of the arm and the door; means guiding the door at a point between the vertical edges of the door, the arm forming one link and the door between the pivotal connection and the guiding means forming the other link of a toggle, and spring means connected with the arm to rotate the latter and close the door.

70 8. A door organization, comprising in combination, a door; hinge means for the door including, an arm, pivot means for the arm supporting the door proximate a doorway, and a pivotal connection between the outer end of the arm and the door at a point between the vertical edges thereof; means guiding the door at a point between the vertical edges of the door, the arm forming one link and the door between the pivotal connection and the guiding means forming the other link of a toggle, and spring means connected with the arm to rotate the latter and close the door.

75 9. A door organization, comprising in combination, a door; hinge means for the door including, a pair of arms, pivot means for each arm for supporting the door proximate a doorway, and a pivotal connection between the outer end of each arm and the door at a point between the vertical edges thereof; means guiding the door at a point between the vertical edges of the door, the arms forming one link and the door between the pivotal connection and the guiding means forming the other link of a toggle, and spring means connected with one of the arms to rotate the latter and close the door.

80 10. A door organization, comprising in combination, a door, a door check, a tubular hinge

- nation, a door; hinge means for the door including, an arm, pivot means for the arm for supporting the door proximate a doorway, and a pivotal connection between the outer end of the 5 arm and the door at a point between its vertical edges; means guiding the door at a point between the vertical edges of the door, the arms forming one link and the door between the pivotal connection and the guiding means forming the other 10 link of a toggle, and spring means connected with the pivot means to rotate the latter and close the door.
11. A door organization, comprising in combination, a door; hinge means for the door including, a pair of arms, pivot means for each arm for supporting the door proximate a doorway, and a pivotal connection between the outer end of each arm and the door at a point between its vertical edges; means guiding the door at a 15 point spaced from the pivotal connection, the arms forming one link and the door between the pivotal connection and the guiding means forming the other link of a toggle, spring means connected with one of the arms to rotate the latter and close the door, and a second spring means urging the door to rotate about its pivotal 20 connection to close the door.
12. A door organization, comprising in combination, a door; hinge means for the door including, an arm, pivot means for the arm for supporting the door proximate a doorway, and a pivotal connection between the outer end of the 25 arm and the door at a point between its vertical edges; means guiding the door at a point spaced from the pivotal connection, the arm forming one link and the door between the pivotal connection and the guiding means forming the other link of a toggle, spring means connected with the pivot means to rotate the latter and close the door, and a second spring means urging the pivotal 30 connection in a direction to close the door.
13. A door organization, comprising in combination, a door; hinge means for the door including, an arm, pivot means for the arm for supporting the door proximate a doorway, and a pivotal connection between the outer end of the 35 arm and the door at a point between its vertical edges; means guiding the door at a point spaced from the pivotal connection, the arm forming one link and the door between the pivotal connection and the guiding means forming the other link of a toggle, spring means connected with the pivot means to rotate the latter and close the door, and a second spring means urging the pivotal 40 connection in a direction to close the door including, means delaying the tensioning of the second spring means until the door is partially open.
14. A door mounting comprising in combination, hinge means for a door including, an arm, pivot means for the arm for supporting the door proximate a doorway, and a pivotal connection on the outer end of the arm pivotally securing the 45 arm to the door; spring means connected with the arm to rotate the latter and close the door, and a door check connected with the pivotal connection and controlling the rotation thereof to control the door closing.
15. A door organization, comprising in combination, a door; hinge means for the door including, an arm, pivot means for the arm for supporting the door proximate a doorway, and a pivotal connection between the outer end of the 50 arm and the door at a point between the vertical edges thereof.

vertical edges; means guiding the door at a point spaced from the pivotal connection, the arm forming one link and the door between the pivotal connection and the guiding means forming the other link of a toggle, spring means connected with the arm to rotate the latter and close the door, and a door check connected with the pivotal connection and controlling the rotation thereof to control the door closing.

16. A door organization, comprising in combination, a door; hinge means for the door including, an arm, pivot means for the arm for supporting the door proximate a doorway, and a pivotal connection between the outer end of the 5 arm and the door at a point between the vertical edges; means guiding the door at a point spaced from the pivotal connection, the arm forming one link and the door between the pivotal connection and the guiding means forming the other link of a toggle, spring means connected with the arm to rotate the latter and close the door, a door check connected with the pivotal connection and controlling the rotation thereof to control the door closing, and spring means connected with the pivotal connection and urging the door to rotate about the pivotal connection to close the door.

17. A door organization, comprising in combination, a door; hinge means for the door including, an arm, pivot means for the arm for supporting the door proximate a doorway, and a pivotal connection between the outer end of the arm and the door at a point between the vertical edges; means guiding the door at a point spaced from the pivotal connection, the arm forming one link and the door between the pivotal connection and the guiding means forming the other link of a toggle, spring means connected with the arm to rotate the latter and close the door, and a door check connected with the pivotal connection and controlling the rotation thereof to control the door closing, and spring means connected with the door check and urging the door to rotate about the pivotal connection to close the door.

18. A door organization comprising, in combination, a door, a doorway for the door; a hinge mounted proximate the doorway including, an arm carried by the hinge, and a pivotal connection on the arm pivotally supporting the door at a point between the vertical edges thereof; means guiding the door at a point spaced from the pivotal support of the arm, the arm forming one link and the door between the pivotal connection and the guiding means forming the other link of a toggle, and a spring disposed in the hinge for swinging the arm and closing said door.

19. A door organization comprising, in combination, a door, a doorway mullion; a hinge mounted in the doorway mullion including, an arm carried by the hinge and a pivotal connection on the arm pivotally supporting the door at a point between the vertical edges thereof; means guiding the door at a point spaced from the pivotal support of the arm, the arm forming one link and the door between the pivotal connection and the guiding means forming the other link of a toggle, and a spring disposed in the hinge for swinging the arm and closing said door.

20. A door organization comprising, in combination, a door, a doorway mullion; a hinge mounted in the doorway mullion including, an arm carried by the hinge, and a pivotal connection on the arm pivotally supporting the door at a point between the vertical edges thereof; a

5 spring disposed in the hinge for rotating the arm and closing said door, means guiding the door at a point spaced from the pivotal support of the arm, the arm forming one link and the door between the pivotal connection and the guiding means forming the other link of a toggle, and means for variably tensioning said spring.

10 21. A door organization comprising, in combination, a door, a doorway for the door; a hinge mounted proximate the doorway for supporting the door between the vertical edges thereof, said hinge comprising, a tube, a pair of laterally extending arms rigidly secured to the ends thereof, and a pivotal connection on the arms pivotally supporting the door at a point between the vertical edges of the door; means guiding the door at a point spaced from the pivotal support of the arms, the arms forming one link and the door between the pivotal connection and the guiding means forming the other link of a toggle, and a spring disposed in the tube for swinging the arms and closing said door.

15 22. A door organization comprising, in combination, a door, a doorway for the door; a hinge mounted proximate the doorway for supporting the door between the vertical edges thereof, said hinge comprising, a tube, a pair of laterally extending arms rigidly secured to the ends thereof, and a pivotal connection on the arms pivotally supporting the door at a point between the vertical edges of the door; means guiding the door at a point spaced from the pivotal support of the arms, the arms forming one link and the door between the pivotal connection and the guiding means forming the other link of a toggle, a spring disposed in the tube for swinging the arms and closing said door, and means for variably tensioning said spring.

20 23. A door organization comprising, in combination, a door, a door check secured to the door; a hinge rotatably mounted proximate a doorway for supporting the door between the vertical edges thereof, said hinge comprising, a pair of laterally extending arms rigidly secured thereto, and a pivotal connection on the arms pivotally supporting the door; one of said arms being operatively connected to the door check to check the closing of the door; means guiding the door at a point spaced from the pivotal support of the arms, the arms forming one link and the door between the pivotal connection and the guiding means forming the other link of a toggle, and a tensioned spring in the hinge tending to close said door.

25 24. A door organization comprising, in combination, a door, a doorway mullion, a door check secured to the door; a hinge rotatably mounted in the doorway mullion for supporting a door between the vertical edges thereof, said hinge comprising, a pair of laterally extending arms rigidly secured thereto, and a pivotal connection on the arms pivotally supporting the door; one of said arms being operatively connected to the door check to check the closing of the door, means guiding the door at a point spaced from the pivotal support of the arms, the arms forming one link and the door between the pivotal connection and the guiding means forming the other link of a toggle, and a tensioned spring in the hinge tending to close said door.

30 25. A door organization comprising, in combination, a door, a doorway for the door; a door check secured to the door, said door check comprising, means for yieldably limiting the extent to which the door may be opened; a hinge ro-

tatably mounted proximate the doorway for supporting the door between the vertical edges thereof, said hinge comprising, a pair of laterally extending arms rigidly secured to the ends thereof, and a pivotal connection on the arms pivotally supporting the door; one of said arms being operatively connected to the door check to check the closing of the door and yieldably limit the extent to which said door may be opened, means guiding the door at a point spaced from the pivotal support of the arms, the arms forming one link and the door between the pivotal connection and the guiding means forming the other link of a toggle, and a spring in the tubular hinge for closing the door.

35 26. A door organization comprising, in combination, a door, a doorway for the door; a door check secured to the door, said door check comprising, means for yieldably limiting the extent to which the door may be opened; a hinge rotatably mounted proximate the doorway for supporting the door between the vertical edges thereof, said hinge comprising, a pair of laterally extending arms rigidly secured to the ends thereof, and a pivotal connection on the arms pivotally supporting the door; one of said arms being operatively connected to the door check to check the closing of the door and yieldably limit the extent to which said door may be opened, means guiding the door at a point spaced from the pivotal support of the arms, the arms forming one link and the door between the pivotal connection and the guiding means forming the other link of a toggle, a spring in the tubular hinge for closing the door, and means for tensioning said spring as the door is opened.

40 27. A door organization comprising, in combination, a door, a doorway mullion; a door check secured to the door, said door check comprising, means for yieldably limiting the extent to which the door may be opened; a hinge rotatably mounted in the doorway mullion for supporting the door between the vertical edges thereof, said hinge comprising, a pair of laterally extending arms rigidly secured to the ends thereof, and a pivotal connection on the arms pivotally supporting the door; one of said arms being operatively connected to the door check to check the closing of the door and yieldably limit the extent to which said door may be opened, means guiding the door at a point spaced from the pivotal support of the arms, the arms forming one link and the door between the pivotal connection and the guiding means forming the other link of a toggle, and a spring in the tubular hinge for closing the door.

45 28. A door organization comprising, in combination, a door, a doorway; a door check secured to the door, said door check comprising means for yieldably limiting the extent to which the door may be opened; a hinge rotatably mounted proximate the doorway for supporting the door between the vertical edges thereof, said hinge comprising, a pair of laterally extending arms rigidly secured to the ends thereof, and a pivotal connection on the arms pivotally supporting the door; one of said arms being operatively connected to the door check to check the closing of the door and yieldably limit the extent to which said door may be opened, means guiding the door at a point spaced from the pivotal support of the arms, the arms forming one link and the door between the pivotal connection and the guiding means forming the other link of a toggle, a spring in the tubular hinge for closing the door, means

for variably tensioning said spring, and means for increasing the tension of said spring as the door is opened.

29. Means for mounting a door comprising a hinge mounted in a doorway for supporting a door between the vertical edges thereof, a spring disposed in the hinge for closing said door, and means for variably tensioning said spring, said tensioning means comprising an anchor and a shaft in said hinge to which the ends of said spring are respectively fixed, means proximate one end of said hinge for rotating said shaft, and means for locking said shaft in various positions.

10 30. Means for mounting a door comprising a hinge mounted in a doorway for supporting a door between the vertical edges thereof, a spring cooperating with the hinge for closing said door, and means for variably tensioning said spring, said tensioning means comprising means for fix-

ing one end of said spring to said hinge, means mounted proximate an end of said hinge for moving the other end of said spring to various positions, and means for locking the last named spring end in said positions.

5 31. A door mounting comprising in combination, hinge means for a door including, an arm, pivot means for the arm for supporting the door proximate a doorway, and a pivotal connection upon the outer end of the arm for connection with the door at a point between the vertical edges thereof; means guiding the door at a point between the vertical edges thereof, spring means connected with the arm to rotate the latter and close the door, and a second spring means connected with the pivotal connection and controlling the rotation thereof to control the door closing.

EDWARD H. ELLISON.
